UNITED STATES PATENT OFFICE.

WILLIAM H. MUSSEY, OF RICHMOND HILL, NEW YORK.

SUSPENSION MEANS FOR MOTOR-GENERATORS.

1,029,622.

Specification of Letters Patent. Patented June 18, 1912.

Application filed February 21, 1912. Serial No. 679,186.

To all whom it may concern:

Be it known that I, WILLIAM H. MUSSEY, a citizen of the United States, residing at Richmond Hill, Long Island, in the county 5 of Queens and State of New York, have invented certain new and useful Improvements in Suspension Means for Motor-Generators, of which the following is a specification.

10 My invention relates to suspension means for a motor generator as employed in conjunction with railway cars.

One of the objects of the invention is to provide suspension means which is slidably 15 adjustable with respect to the truck, and involves suitable tensioning devices which are regulatable to secure the desired connection between the front axle of the trailer truck and the motor generator.

20 Another object of the invention is to provide means for thoroughly absorbing the shock ordinarily brought to bear on the motor generator and its subsidiary parts, which occurs when the belt connection between the 25 front axle and the pulley of the generator is broken.

25 A further object sought by the invention is to provide a novel arrangement of swing link suspension in which the generator is supported from the top of the links, the latter having their bearing at the base, or below the generator.

Still another object contemplated by the invention is the provision of a plurality of 35 tensioning means, either of which may be adjusted independently of the other to tighten or loosen the belt connection, as occasion may require.

30 A still further object of the invention is the provision of a support, which virtually constitutes a part of the truck, said support being designed to permit of ready removal of the motor generator, and easy access to its associated parts.

45 To the accomplishment of the recited objects and others coördinate therewith, the preferred embodiment of my invention resides in that construction and arrangement 50 of parts hereinafter described, illustrated in the accompanying drawings, and embraced within the scope of the appended claims.

In said drawings: Figure 1 is a top plan view of the support for the suspension means, and Figs. 2 and 3 are respectively, 55 end and side elevations of the same. Fig. 4

is a plan view of the sliding base, and Figs. 5 and 6 are respectively, end and side elevations of the device. Figs. 7, 8 and 9 are detail views of one of the suspension links for the generator. Figs. 10, 11, 12 and 13 60 are detail views of another form of suspension link. Figs. 14, 15 and 16 are respectively, a plan view, a side elevation, and end elevation of one of the angle irons used in forming the support. Figs. 17, 18, 19, 20 and 21 are detail views of the various devices used for securing an adjustment of the tensioning means.

Referring more particularly to the drawings for a detail description of my invention, the numeral 1 designates the front cross beam of an ordinary truck, the same connecting the supplemental longitudinal beams 2, which in turn are fastened together by the channel iron 3. The longitudinal beams 70 2 and the two cross or intermediate connecting beams 1 and 3 serve as an efficient support for the suspension means embodied in my invention. Secured to the cross beams 75 1, as at 4, are the angular terminals 5 of the angle irons 6, more clearly shown in Figs. 14, 15 and 16. As will be observed upon inspection of Fig. 3, these angle irons 6 extend slightly below the plane of the cross beam 1 and project longitudinally therefrom to occupy superimposed positions with respect to the front beam 3, the said angle irons being suitably secured by means of the 80 rivets 7, or other equivalent fastening means.

85 Arranged transversely of the angle irons 6 is a bed-plate as best shown in Figs. 4, 5 and 6 of the drawings. This bed-plate comprises a suitable skeleton metallic piece formed with flanges 9 and 10 at its opposite edges, the said flanges being longitudinally slotted as at 11, and furthermore provided with end bearings 12 and 13. Suitable bolts, as 13^a, extend upwardly through the apertures 14 in the angle iron and the slots 11 of the flanges 13 of the bed-plate 8, the said bolts being threaded and provided with nuts, as 14^a, which prevent any upward displacement of the said bed-plate with respect to the support formed by the angle irons, and at the same time permit of a 90 slidable movement of the bed-plate upon said angle irons when it is desired to adjust the connection between the motor generator and the rear axle.

100 The bearings 12 and 13 carried by the

bed-plate are designed to receive the trunnions 15 and 16 of the respective suspension links 17 and 18, and suitably secured thereto in any well known manner. As exhibited in Figs. 7, 8 and 9, the suspension link 17 comprises a suitable piece of metal with its extremities 19 and 20 bent at right angles to the main or body portion 21. The deflection 19 is perfectly straight, while the opposite deflection 10 is curved outwardly, and the main body portion is provided with an elongated bearing 22 adjacent the angle portion 19. The opposite suspension link 18, as shown in Figs. 10, 11, 12 and 13, is similar to the suspension link just described, with the exception of the opposite curve given to the arm or angle portion 20, and the provision of a vertical projection 23 on the end of trunnion 16. As clearly shown in Figs. 1, 2 and 3, the suspension links have their trunnions loosely mounted in the bearings 12 and 13 of the base 8 and extend upwardly therefrom to present a support for the motor generator, which is indicated by dotted lines. This generator is preferably secured to the elongated bearings 22 of the links by the coupling members 24, and the pulley 25, of the generator extends between the said links so as to allow ready connection of the same with the belt which is passed over the front axle of the trailer truck.

Pivottally connected to the vertical projection 23 of the suspension link 18, as at 26, is a nut 27, which is illustrated in Figs. 19, 20, 35 and 21 of the drawings, and comprises a cylindrical portion 28, a terminal eyelet 29, and a plurality of longitudinally arranged elongated slots 30. Furthermore, this nut 27 is provided with internal screw threads 40 which engage the corresponding threads of the shank 31 of the nut 32, the said shank extending on the opposite side of the nut through the vertical bracket 33 and then for a short distance to permit the reception of a 45 small cushioning spring 34, a nut 35 being secured on the outer extremity of said shank to hold and regulate the tension of said spring. A larger spring, as 36, is interposed between the bracket 33 and the nut 32. The 50 terminal of the shank 31 which projects into the hollow nut 36 is provided with a plurality of apertures as 37 which are designed to receive the extremities of a cotter pin or the like in order to permit of a fine adjustment 55 of the spring 36. The opposite end of said shank 31 may also be provided with a plurality of openings 38 for the same purpose in connection with the spring 34.

When it is desired to adjust the tension of 60 the main spring 36 the cotter pin is removed and the nut 32 rotated in the desired direction. If occasion should require tightening of the belt connection, the nut 32 will be loosened so as to permit the main spring 36 65 to exert an expansive action upon the lower

vertical projection 23 of the suspension link, this being in turn transmitted to the body of the generator. I have also found it desirable to employ a separate means for independently securing an adjustment of the 70 spring tensioning device, the same consisting of forming a pair of vertical lugs 39 arranged medially of the base-plate 8, providing the terminals of these projections with a pair of alined openings as 40, and inserting 75 the eyelet 41 of the rod 42, and suitably connecting the same by the transversely extending bolt 43. As will be noted upon examination of Fig. 2 of the drawings, the rod 42 extends across the front beam 3 and rests in 80 the vertically arranged bracket 44. The outer extremity of this rod 42 is screw threaded, as at 45, and carries nuts 46 and 47. In resorting to this independent means the nuts 46 and 47 are loosened, the nut 47 again tightened in its desired position and the nut 46 brought to bear on the end of nut 47 to serve as a lock nut.

By virtue of the curvilinear projection formed on the suspension links, I am enabled to disconnect the motor generator and remove the same laterally from the supporting means on the side of the truck opposite the side where the springs 36 and 34 are arranged, and transport the same to any desired place. Furthermore, when the bed-plate is once lined up, due to the method of application hereinbefore described, the generator will always remain in line with, or parallel to the truck axle. 100

What is claimed, is:—

1. In a support for generators, the combination of a truck, an adjustable bed-plate mounted on said truck, a pair of suspension links pivoted to said bed-plate, a generator connected to said links, and an adjustable tensioning means connected to one of said links and said bed-plate. 105

2. In a support for generators, the combination of a truck, a slidable bed-plate mounted on said truck beneath the generator, suspension links carried by said bed-plate, and tensioning means connected to one of said links and said bed-plate. 110

3. In a device of the character described, the combination of a truck, a generator, and a pair of arched links for supporting said generator, said links permitting the removal of the generator laterally from the truck. 115

4. In a device of the character described, the combination of a truck, a swinging support, and a generator connected at the top of said support, said support permitting the removal of the generator laterally from the truck. 120

5. In a device of the character described, the combination of a truck, a slidable bed-plate mounted on said truck, suspension means carried by said bed-plate, tensioning means connected to said suspension means, 125

means for adjusting said tensioning means, and means independent of the last mentioned means for regulating said tension.

6. In a device of the character described, 5 the combination of a truck, a slidable bed-plate on said truck, suspension links pivoted to said bed-plate, a generator pivoted to said links, and adjustable tensioning means connected to one of the said links and said bed-plate.

7. In a device of the character described, 10 the combination of a truck, a slidable base-plate mounted on said truck, suspension means carried by said bed-plate, adjustable tensioning means associated with said suspension means, and yieldable shock-absorbing means connected to the tensioning means.

8. In a device of the character described, 15 the combination of a swinging support, a generator connected to the top of said support, and tensioning means in operative relation with the support.

9. In a device of the character described, 20 the combination of a swinging support, a generator mounted on said support at a point above the axis of the latter, and tensioning means for the support.

10. In a device of the character described, 25 the combination of a slidably adjustable bed-plate, a support carried by said bed-plate, a generator connected to the top of the support, and tensioning means.

11. In a device of the character described,

the combination of a bed-plate, an arched support, a generator connected to the top of said support, and tensioning means in operative relation with the support.

12. In a device of the character described, 30 the combination of a bed-plate, a pair of arched links pivoted to said bed-plate, a generator mounted on the upper portions of said links, and tensioning means between the bed-plate and links.

13. In a device of the character described, 35 the combination of a bed-plate, a pair of substantially inverted U-shaped links pivoted to said bed-plate, one of the outer vertical portions of each link being outwardly curved, a generator mounted on the upper 40 ends of said links, and tensioning means between the bed-plate and links.

14. In a device of the character described, 45 the combination of a bed-plate, a pair of generator suspension links pivoted to said 50 bed-plate, a bracket carried by the bed-plate, a cushioning spring on one side of the bracket, a tensioning spring on the other side of said bracket, a rod extending through the bracket and springs and connected to one of said links, and means for adjusting the tension of said springs.

In testimony whereof I hereunto affix my signature in presence of two witnesses.

WILLIAM H. MUSSEY.
